DENTAL DRILLING INSTRUMENT

Charles Howard Clark, Pitman, N. J.

Application April 12, 1935, Serial No. 16,086

6 Claims.

(Cl. 32—27)

This invention relates to improvements in dental drilling instruments, and a principal object of the invention is to provide a novel construction facilitating replacement of the operating parts when such replacement becomes necessary by reason of excessive wear.

Dental drills are necessarily precision instruments and must be manufactured to relatively close tolerances. The instruments also by reason of their relatively high operating speeds are subject to wear, which interferes with the precise operation required in tools of this character. Heretofore the instruments have been so constructed that the repairs required to maintain them in efficient operating condition involved difficult and time-consuming operations beyond the capacities of the average practitioner and reconditioning was, therefore, a factory operation involving a considerable expense and loss of time.

An object of the present invention, therefore, is to provide a construction making possible immediate repair of worn instruments by the practitioner, and to thereby avoid the undue expense and delay attending such repairs on instruments of the prior construction.

More specifically the invention contemplates the provision in an instrument of this character of a unit mechanism including the rotary chuck 30 in which the burr is detachably inserted together with the bearings for said chuck, with provision for detachably mounting this unit in proper position within the casing of the instrument, and the invention further resides in the novel mechanical and structural details and elements by means of which this end is attained.

In the attached drawing:

Figure 1 is a side and partial sectional view of an instrument made in accordance with my invention;

Fig. 2 is an enlarged fragmentary sectional view of the head end of the instrument;

Figs. 3, 4 and 5 are views in perspective of elements of the casing or housing, and

Fig. 6 is a view in perspective of the unit mechanism constituting the essential novel feature of the invention.

With reference to the drawing, an instrument embodying my invention may comprise the usual hollow shank 1 which houses the operating elements of the drill and which in the present instance comprises two separable parts 2 and 3 meeting on a longitudinal dividing line 4. The parts 2 and 3, as shown in Figs. 3 and 4, have abutting flat surfaces and are held together by means of a sleeve 5 which embraces and receives the threaded extremities 2a and 3a of the parts. By means of the threads, the beveled shoulder 6 of the shank 1 is drawn firmly down upon a cor-

respondingly formed seat 7 in one end of the sleeve 5.

As shown in Fig. 2, the shank 1 is provided with a longitudinal bore 8 which receives and constitutes a journal for a shaft 9 which projects at one end into the sleeve 5, and this projecting end of the shaft is coupled in the usual manner to a flexible shaft 11 which extends into the open end of the sleeve 5 and which is connected to the source of power. The shaft 9 at its inner end 10 carries a toothed pinion 12 which in assembly meshes with a pinion 13, this pinion in the present instance being shown as an integral part of a sleeve 14 mounted for rotation in the head end 15 of the shank 1. The sleeve 14 is journaled in 15 a bearing comprising telescoping parts 16 and 17, which bearing as shown in Figs. 2 and 6 embraces the sleeve and is cut away at one side to expose the pinion 13 for engagement with the pinion 12 and to provide the recess required for 20 reception of the latter pinion.

In assembly, the flat face 18 of the cut-out portion of the bearings 16 and 17 lies flush against a corresponding flat surface 19 on the inside of the shank element 3, see Fig. 4, whereby 25 the elements 16 and 17 are held against rotational movement within the shank. The reduced extremity 21 of the bearing element 16 is threaded, and in assembly is received by the internally threaded head end of the shank element 2, and 30 in accordance with my invention, the bearing elements 16 and 17 are secured together either by welding or soldering, as indicated at 22, or in any other suitable manner. It will be apparent, therefore, that the sleeve 14 with its pinion 13 35 and the bearing elements 16 and 17 constitute a unit which may be inserted and detached from the shank 1 at will and which when inserted in the shank is firmly secured and positively positioned within the latter.

In assembling the instrument, the sleeve 5 is unthreaded from the shank 1, thereby permitting separation of the elements 2 and 3. The unitary mechanism consisting of the sleeve 14, pinion 13 and bearing elements 16 and 17 is then 45 threaded into the shank element 2, these parts being so relatively formed that when the shoulder 23 of the element 16 is firmly engaged with the abutting shoulder of the element 2, the face 18 will extend at right angles to the axis of the 50 bore 8. The shank element 3 by reason of the face 19, which as previously set forth engages the face 18 of the unit mechanism, is adapted to be used as a wrench to adjust the unit into an accurately aligned position. It is now possible 55 to insert the shaft 9 so that its pinion 12 meshes with the pinion 13, after which the shank element 3 is brought together with the element 2 and assembled with the sleeve 5 as previously described. It will be noted that the shaft 9 60

is provided intermediate its ends with a collar 24 which in assembly engages the end of the shank 1 and functions with the pinion 12 to maintain the shaft 9 in axially fixed position 5 within the shank.

The sleeve 14 is adapted to constitute a chuck for the detachable burrs or tools 25, the shank of these burrs being adapted to neatly fit the bore of the sleeve 14 and being provided adjacent 10 its inner end with a flat 26 which in assembly engages a corresponding flat surface 27 in the sleeve 14 whereby the burr is fixed, rotatably, to the sleeve. In accordance with the usual practice, the end of the shank of the burr 25 is 15 provided with a circumferential groove 28 which receives the hooked end of a clip 29 adjustably secured to the shank element 3, as best shown in Fig. 5, this clip functioning to clamp the burr 25 against axial movement within the chuck 14. 20 In the present instance, the clip 29 is pivotally mounted at 31 within a slotted recess 32 in the shank element 3, and the resilient tool end 33 of the clip is provided with a ball-like projection 34 which when the clip is in the burr-retaining 25 position engages in the outer end of a port 35 in the shank to thereby retain the clip securely in its operative position. The projection 34 also functions to close the outer end of the port 35 which is adapted to function as a passage for 30 admission of a lubricant to the journal 8 of the shaft 9.

It will be noted that in the aforescribed construction all of the rotating or working parts of the mechanism are readily detachable from 35 the casing or housing, and are so formed as to be readily replaceable by new parts when required. If by reason of wear either in the rotary chuck element 14 or in the journal elements 16 and 17 an excessive amount of play 40 develops in these working parts, it is only necessary for the practitioner to separate the shank elements 2 and 3, remove the shaft 9 with its pinion 12, and to then release the unit mechanism consisting of the other working parts by unscrewing 45 the unit from the shank element 2. This may readily be accomplished by utilizing the shank element 3, as previously described, as a wrench. The unit mechanism may then be replaced by new mechanism of the same construction and 50 the instrument re-assembled for immediate use. This operation being well within the capacity of the practitioner himself, all the delays and a substantial proportion of the expense heretofore involved in such repairs are avoided. It will be 55 apparent also that the construction facilitates maintenance of the instrument in clean, sanitary and well lubricated condition.

It will be understood that the invention is capable of other embodiments than that illustrated.

60 I claim:

1. In a dental instrument of the character described, the combination with a casing, of operating mechanism comprising a drive shaft journaled in the casing, a rotary chuck, a bearing for the chuck constituting the sole chuck-supporting means, and means for operatively connecting the chuck to the shaft; said casing being formed interiorly with a seat for said bearing in 65 which said bearing is held detachably in fixed 70 predetermined position with respect to said shaft, and said chuck and bearing being formed as a unit, and as such being insertible in and detachable from the casing.

2. In a dental instrument of the character described, the combination with a casing, of a drive shaft journaled in the casing; a gear carried by the shaft; a unitary mechanism comprising a rotary chuck; a bearing constituting the sole 5 means for supporting said chuck; and a gear carried by the chuck and adapted for engagement with the said drive gear; said casing and bearing being formed with complementary surfaces affording the latter a seat within the casing, and 10 said mechanism being insertible in and detachable from the casing as a unit.

3. In a dental instrument of the character described, the combination with a casing having a longitudinal bore, and a socket extending at an angle to said bore, of a drive shaft journaled in the bore and having a pinion extending into said socket; and a unit mechanism comprising a rotary chuck; a bearing non-rotatably and detachably seated in said socket and constituting 20 the sole supporting journal for said chuck; and a pinion carried by the chuck and meshing with said drive pinion, said casing and bearing being formed with complementary surfaces affording the latter a seat within the casing, and 25 said mechanism being insertable in and detachable from said casing as a unit.

4. In a dental instrument of the character described, the combination with a casing having longitudinally separable sections and means for securing said sections together, said sections having registering recesses at one end forming a transverse socket, a longitudinal drive shaft journaled between said sections and having a pinion extending into said socket, and a unit mechanism seating in said socket and comprising a bearing member threaded into the recess of one of said sections, a rotary chuck journaled in said bearing member, and a gear carried by said 30 chuck and meshing with said drive gear, said 35 drive shaft and the unit mechanism being detachable from the casing by separation of said 40 casing sections.

5. In a dental instrument of the character described the combination with a casing having longitudinally separable sections and means for securing said sections together, said sections having registering recesses at one end forming a transverse socket, a longitudinal drive shaft journaled between said sections and having a pinion extending into said socket, and a unit mechanism seating in said socket and comprising a bearing member threaded into the recess of one of said sections and having a non-rotatable releasable connection with the other section, a 45 rotary chuck journaled in said bearing member, and a gear carried by said chuck and meshing with said drive gear, said drive shaft and the 50 unit mechanism being detachable from the casing by separation of said casing sections.

6. In a dental instrument of the character described, the combination with a casing, of operating mechanism comprising a drive shaft journaled in the casing; a rotary tool chuck, a bearing for the chuck, and means for operatively connecting the chuck to the shaft; said casing and bearing being formed with complementary surfaces affording the latter a seat within the casing, and 65 said chuck and bearing being formed as a unit, and as such being insertible and detachable from 70 the casing; and means on said casing for releasably locking the said tool in the chuck.

CHARLES HOWARD CLARK.
